UNITED STATES PATENT OFFICE.

WILLIAM HITER MACGILL, OF LOUISVILLE, KENTUCKY.

TIE-OUT.

No. 926,664.

Specification of Letters Patent.

Patented June 29, 1909.

Application filed April 6, 1908. Serial No. 425,453.

To all whom it may concern:

Be it known that I, WILLIAM HITER MACGILL, a citizen of the United States, residing at Louisville, in the county of Jefferson and State of Kentucky, have invented a new and useful Tie-Out, of which the following is a specification.

This invention relates to devices for tying up bundles and packages, and especially for tying out packages of letters and the like in the post office, and some of the objects of my improvement are, saving in the cost of twine; to simplify the process of tying out; to provide means for tying out which shall be reliable in operation, and thus prevent scattering and loss of letters; to use the same tie-out many times; to provide a tie-out which will obviate the necessity of using scissors for opening packages and keeping the scissors sharp; to provide a tie-out which will be clean and sanitary; and to avoid sharp points and angles which might injure envelops, wrappers or the hands of user. These objects I attain by means of the device illustrated in the accompanying drawings, in which—

Figure 1 is a perspective view of a package of letters as tied out with my device; Fig. 2, a plan view of the device; Fig. 3, a detail sectional view of the disks; and, Fig. 4, a detail view of the catch.

Similar reference numerals refer to similar parts throughout the several views of the drawing.

A flat plate or disk 1 is provided with a second disk or button 2, attached thereto by a rivet 3 or in any other suitable manner, and a string or cord 4. To the free end of string 4 is attached a catch 5, for securing to the body of the string at any intermediate point between catch 5 and plate 1. The button 2 is preferably made dish shaped, so as to leave a space between its rim and the surface of plate 1. String 4 is preferably attached to plate 1 at a point diametrically opposite that at which button 2 is attached. Any other form of flat material may be used instead of the disks 1 and 2 shown that perform the same function without departing from the spirit of my invention. I prefer to use disks, and to make their edges smooth and rounding, to avoid points or other sharp

edges which may tear envelops or wrappers on adjacent packages or injure the hands of the user. It will be understood that by using such disks, packages of letters or other articles may be thrown upon each other and slid upon one another without injury. This is an important feature, since in post-offices it is necessary to handle the mail matter rapidly and to avoid the mental strain incident to taking care not to injure the wrappers. I have shown plate 1 centrally perforated, to provide means for conveniently hanging up the tie-outs upon pegs or racks near the place where they are to be used. This perforation also serves to lighten the plate. The catch 5 is preferably made of spring wire, coiled as shown, the coils being close, so that when the catch is passed over the string 4, it holds thereon by friction.

In use, the plate 1 is placed upon the package 6, as shown, the thumb is placed upon the plate at 7 while the package 6 is grasped in one hand. With the other hand string 4 is passed around the package, as shown in Fig. 1, in a longitudinal vertical plane, then looped over button 2, passing it between button 2 and plate 1, then around package 6 in a transverse vertical plane as shown, then looped again over button 2, the free end drawn tight, and catch 5 finally secured on the string. It will be understood that if package 6 is so large that it fills the capacity of the string, catch 5 will be secured to the string near the place where it is secured in plate 1. If the package is smaller, the catch 5 is passed around to the opposite side of the package and is secured there. In this way no loose end is left dangling from the package, but the entire string is utilized in wrapping, and a neat package without the danger of becoming untied is the result. When the package is untied, the string is not cut with scissors, or in any way, as is done at present, but catch 5 is simply released and the string unwound from the package. The string being wedged between disks 1 and 2, is held by friction, so that the strain does not come upon catch 5, and the function of the catch is therefore simply to hold the free end of the string in place. It is contemplated to make the tie-outs in several

sizes, so that packages of different sizes may be tied out without a surplus string.

Having thus described my invention, I claim—

5 A tie-out for packages, comprising flexible means for tying, a centrally perforated disk secured to said flexible means for tying,

looping means attached to said centrally perforated disk, and a catch attached to said flexible means for tying.

WILLIAM HITER MacGILL.
